WINDOW

William D. Bayley, Springfield, Ohio

Application April 30, 1938, Serial No. 205,216

24 Claims. (Cl. 189—64)

This invention relates to windows and in more particular to metallic or fabricated windows, terminating in spaced relation from the masonry extending along the bottom of the opening.

5 This application is a continuation-in-part of my copending application Serial No. 115,752, filed Dec. 14, 1936 for Detention window and method of glazing same.

In the construction of metallic windows, especially metallic windows utilizing metals that are very susceptible to electrolytic action in the presence of moisture and the masonry bounding the window, the metallic portions eat away or corrode most rapidly along the sill of the window.

10 15 This corrosion presents a very serious problem in certain industries, as for example, the packing industry, where there is a great amount of steam and vapor present in the air. In such places it is necessary to replace the windows at intervals, due 20 to corrosion along the sill.

An object of this invention relates to the method of constructing and arranging the masonry surrounding the window.

Another object of this invention is to provide 25 a sill-less window wherein the lower glass pane is embedded in the masonry extending along the bottom of the window.

Another object of this invention is to provide a window that is cheap, efficient, easily constructed, but at the same time dependable.

30 Another object of this invention is to reinforce the bottom portion of a metallic frame structure.

Another object of this invention is to provide 35 a main body portion of a window structure that terminates in spaced relation from the bottom of the window opening and an auxiliary structure disposed intermediate the main frame portion and the bottom of the window opening.

40 Another object of this invention is to provide a fabricated window frame structure for a portion of the window opening and a cast frame portion for the remainder of the window opening.

Other objects and advantages reside in the 45 construction of parts, the combination thereof and the mode of operation, as will become more apparent from the following description.

In the drawings,

Fig. 1 is a front view of a window.

50 Fig. 2 is a vertical sectional view taken substantially on the line 2—2 of Fig. 1.

Fig. 3 is a horizontal sectional view taken substantially on the line 3—3 of Fig. 2.

55 Fig. 4 is a fragmentary sectional view of a modification.

Fig. 5 is a fragmentary sectional view taken substantially on the line 5—5 of Fig. 4.

Fig. 6 is another fragmentary sectional view similar to Fig. 4; but looking in the opposite direction.

Fig. 7 is a fragmentary front view of another modification.

Fig. 8 is a fragmentary sectional view taken substantially on the line 8—8 of Fig. 7.

Fig. 9 is a horizontal sectional view of another 10 modification showing H-shaped muntin bars.

Fig. 10 is a sectional view of another modification.

Fig. 11 is a sectional view taken substantially 15 on the line 11—11 of Fig. 10.

Fig. 12 is a sectional view of a form-structure suitable for use in making the sill disclosed in Fig. 10.

Fig. 13 is a fragmentary sectional view of 20 another modification.

Fig. 14 is a fragmentary sectional view of another modification of a form-structure detail.

In metallic window constructions, both for use in commercial buildings and for use in penal institutions, the metallic parts such as steel in contact with the masonry, will corrode in certain parts of the window structure, particularly along the sill portion. The corrosion commonly spreads upwardly to the portions that project upwardly from the masonry. Use has demonstrated, particularly in packing houses and elsewhere where windows are subjected to steam and to chemical fumes, that the life of the bottom horizontal portion of a steel window is much shorter than the life of other portions of the window. A reason 30 for this is that the bottom portion is sometimes partially embedded in the masonry and therefore inaccessible for repainting. Moisture and dampness is a common condition thereof. It is a well known electrochemical phenomenon that 35 electrolysis will erode the metal when in the presence of moisture and in the presence of other chemical elements or compounds thereof. The upper portions of the window are better positioned to drain and are therefore not subject to 40 as much moisture as the sill portion.

It is not only water that may give trouble; but chemicals added to the water will accelerate this erosion. In factories where chemical fumes are prevalent or where chemical dust particles float in the air, the erosion may be greatly accelerated, so that the metallic sill portion of the window is eaten away in a comparatively short time.

It is not commercial windows alone that may 45 be thus affected. Detention windows are also 50 55

liable to have a greater weakness due to the type of steel used in detention bars. Corrosion of the detention bars resulting in a failure may be disastrous. Attempts have been made to "Bonderize" or "Parkerize" the exposed portions of the metallic windows; but this has not proved very satisfactory, as the treatment of the surface of the metallic parts is not very effective over a period of years.

10 In the present embodiment this problem has been solved by terminating the metallic structure in spaced relation from the masonry extending along the bottom of the window opening. By so doing, no metal comes in contact with the 15 masonry. The space between the masonry along the bottom of the window and the lowest portion of the metallic frame structure is closed by glazing, having the upper edge seated against the lowest portion of the metallic frame and the lower edge secured directly to the masonry extending across the bottom of the window by putty or other suitable plastic material.

15 In the preferred embodiment an arrangement of channels has been made wherein it is possible 20 to seat the glazing in channels on all sides without having a side of the channel removable. This has been accomplished by providing oppositely disposed end channels, at least one of which is sufficiently deep to pass the window pane 25 into the channel and slip the opposite edge of the window pane into the other end channel. In order to do this it has been found necessary to make the channel along one side of the window pane sufficiently wide so as to provide clearance beyond 30 the face of the muntin bar for the window pane. In other words, the channel in the wall has been made sufficiently wide so as to extend beyond the inner face of the muntin bar a distance sufficiently great to accommodate the thickness of the 35 glazing.

40 In commercial windows, that is, windows used in buildings other than penal institutions, the metallic fabricated frame is constructed to terminate in spaced relation from the bottom of the 45 window. The intervening space between the bottom of the window and the fabricated frame may be provided with a cast frame, which is inherently slow corroding. As a further safeguard, this cast frame may be removably mounted for 50 replacement whenever it has corroded beyond usefulness. In some installations, the space along the bottom may be used as a ventilating area, closed by a movably mounted closure. This permits the use of a comparatively cheap frame 55 structure for the main portion of the window, wherein the more vulnerable portion of the window is provided with a frame that is made from material having rust resistant qualities and which may be replaced whenever the useful life thereof 60 has ended.

65 Referring to the drawings, the reference character 20 indicates a plurality of vertically disposed detention bars having the upper ends seated in the masonry 22 bounding the ventilating area. The detention bars are held in fixed spaced relation by a plurality of transversely disposed duo-functional rail and muntin bars 24. The ends of the muntin bars 24 preferably extend into the masonry bounding the window opening. 70 The lower ends of the detention bars 20 are arranged in spaced relation from the masonry 26 extending across the bottom of the window. The masonry along the bottom may include a horizontal portion 28, a shoulder 30 and a sloping portion 32. It has been found that the bottom 75

horizontal rail which contacts the sill of the building, and other bars which come close to the sill, rust and deteriorate rapidly. In order to eliminate this rusting and deterioration the lower horizontal and lower ends of the detention bars have been arranged in spaced relation from the masonry or other wall material extending across the bottom of the window.

80 In order to provide a satisfactory support for the lower portion of the detention bars, the lower duo-functional rail and muntin bar designated by the reference numeral 34 has been spaced only a short distance from the masonry extending across the bottom of the window. The spacing of the sill may be only an inch, two inches, or possibly four or five inches from the bottom. The duo-functional rail and muntin bar 34 may be of heavier material, or differently shaped than the other rail bars. This structure requires a bar of much greater strength than if the detention bars 85 were embedded in the masonry long the bottom of the window. In some respects, the duo-functional rail and muntin bar may be referred to as a sill, supporting the lower end of the detention bar 20.

90 The duo-functional rail and muntin bars 24 and 34, respectively, are preferably provided with a slightly sloping portion 36 terminating in a downwardly projecting flange 38 extending along the outside of the detention bars 20. The slope of portion 36 expedites water drainage. The opposite end of the downwardly sloping portion 36 supports and is integral with an H-shaped portion 40. The upper channel 42 is smaller or shallower than the lower channel 44 and these channels receive the closure.

95 As the duo-functional muntin and rail bars 24 and 34 respectively, have their outer ends seated in the masonry bounding the window, the outside frame of the conventional windows has been eliminated.

100 By referring to Fig. 3, it can be readily seen that the channel 50 in the masonry on the right hand side is much narrower than the channel 52 shown on the left hand side in Fig. 3. The spacer 105 bar 56, suitably welded to the muntin bars 24 and 34, forms an inner wall for the channel 52. The channels may be formed by suitable form members described in my application Serial No. 115,752 filed Dec. 14, 1936 for Detention window 110 and method of glazing same. The method of inserting the glazing has also been fully described in the above referred to application.

115 In the modification disclosed in Figs. 4, 5 and 6, like reference numerals have been used to indicate parts like those shown in the preferred embodiment. In this modification post-like tubular member 60, embedded in the masonry along the bottom of the window, extends upwardly and encloses the lower end 62 of one of the vertical 120 bars 20, so as to strengthen and reenforce the lower portion of the window structure. One or more of these tubular members may be used, depending upon the size of the window and the requirements thereof. The upper end of the tubular member 60 is seated between the H-shaped portion 40 and the downwardly projecting flange portion 38 of the muntin bar 34, so that the muntin bar 34 forms a capping member for the tubular portion, thereby preventing water from collecting within the tubular member. This post-like member functions to provide weight bearing supports and it may also provide supports for the glazing panes of less width than the width of the window. This post-like member may be 125

made from cast material, from suitable vitreous or ceramic material or tiling. In the modification disclosed, a web 64 cooperates with a body portion 66 to form a glazing seat supporting the glazing extending along the bottom of the window. Portion 66 may be integral with the tubular sleeve 60 or it may be welded thereto, or secured thereto in any other suitable manner. This tubular sleeve, or post-like member, has been shown in aligned relation with respect to one of the detention bars. It need not necessarily be aligned with a detention bar. It may be off-set from the detention bars. Instead of one post-like member 60, any desired number may be used.

The preferred embodiment and the modification described above are particularly suitable for use as detention windows built into a rail guard assembly or security window for use in preventing trespassing.

In the modifications disclosed in Figs. 7 to 9, the upper portion, including the transversely disposed muntin bars 70 and 72, has been made from rolled steel and simulates any of the conventional commercial metallic windows now on the market. The bottom muntin bar 74 is arranged in spaced relation from the bottom of the window opening. This is to prevent corrosion of the main portion of the window. The corrosion is the greatest along the bottom of the window, that is, where the metallic parts, especially metallic parts made of rolled steel, come in contact with the masonry along the bottom. This corrosion may be in part due to lack of sufficient drainage.

In some types of structures a single window pane may be used. The window pane has the upper portion thereof supported by the lower portion of the metallic frame and the extreme sides and the bottom edges of the window pane supported by masonry bounding the opening. This type of structure has its limitation. It is excellent in small windows; but impractical for large windows, especially where the span is comparatively great or for some other reason a single window pane is not satisfactory. In such structures several window panes are arranged longitudinally across the window below the lowest muntin bar. These window panes may be supported by post-like members 60 or independently thereof.

An auxiliary cast metal frame 80 may be used for enclosing the lower portion of the window opening and for supporting the lower portion of the fabricated main frame. The cast frame 80 may include a sill portion 82 provided with a downwardly projecting flange 84, as shown in Fig. 8, and vertical muntin bar sections 86 of any suitable contour. Bars 86 may be T-shaped as used in Figs. 7 and 8, or H-shaped bars 106, as shown in Fig. 9, may be used, wherein the channel along one side designated by reference character 88 is of less depth than the channel 90 on the opposite side. The side portions 92 probably would be provided with outwardly projecting flanges 94 adapted to face the masonry. The cast metal frame provides a slow corroding portion for the more vulnerable portion of the window. The smaller portion of the window subject to the greatest effect of the elements may be renewable.

The upper ends of the muntin bar sections 86 may be provided with upwardly extending projections 89 passing through the sill 74 of the fabricated frame portion, so as to position the main frame portion and the auxiliary frame portion in fixed relation with respect to each other.

The lower frame may be secured to either the upper frame or to the masonry or to both. The muntin bar 74 may be provided with a downwardly projecting portion 96 and may also be provided with another downwardly projecting portion 98. The web portion of the muntin bar sections 86 is preferably projected up against the web of bar 74. This lower frame portion need not have an upper horizontal bar or there may be a horizontal bar connecting the upper ends of members 86 and 92. The stem or the portion corresponding to the stem of member 82 is preferably curved, so as to permit removal of this lower frame and replacement thereof, should fatal corrosion occur.

In the modification disclosed in Fig. 10, instead of an auxiliary frame portion being used, muntin bar sections 100 have been mounted between the sill 74 of the fabricated main window portion and the masonry extending along the bottom of the window. Either one or both ends of the muntin bar sections 100 may be provided with laterally extending ears 102 and 104. The ear 102 is provided with a suitable aperture for receiving the bolt 106 embedded in the masonry extending across the bottom of the window. The bolt 108 extends through a suitable aperture in the ear 104 registering with an aperture in the muntin bar 74. The bolts 106 and 108 cooperate to hold the muntin bar sections in fixed position with respect to the fabricated window frame and the masonry along the sill of the window. Either one of these bolts may be eliminated for some installations where only one end of the muntin bar section 100 is secured in position. Any other suitable means for securing the auxiliary frame in position may be used. A suitable rod or spacing member 110 may be passed through the muntin bar sections 100, so as to properly align these multiple sections 100 when being placed in position. This retaining rod 110 may be located in any suitable position in the muntin bar sections 100. The muntin bar sections 100 may be T-shaped, I-shaped, H-shaped or any other shape.

The bolts 106 must be accurately positioned in the masonry so as to have the proper relation with respect to the window structure. A slight displacement of the bolts or a slight misalignment is very noticeable. The bolts 106 may be positioned in the masonry across the bottom of the window opening by mounting these bolts in the wood forms for shaping the concrete, as best seen in Fig. 12. These forms may include verticals 112 and a pair of capping members 114 and 116, the capping member 114 being inclined and extending beyond the lower surface of the capping member 116. A suitable strip of sheet metal 118, provided with properly spaced apertures, is used to tie the capping members 114 and 116 together and to form supports and seats for the bolts 106, which are thereby properly positioned relative to the grooves which position the window.

In the modification disclosed in Fig. 13 a stub muntin bar 120 spanning the bottom portion of the window is attached to the muntin bar 74 of the fabricated window structure. The muntin bar 120 is preferably T-shaped in cross sectional area. The web of the muntin bar near the end is provided with an elongated U-shaped cut-away portion 122. A nut 124 is welded to the sides of the U-shaped cut-out portion. This nut 124 is arranged to receive a bolt 126 in the muntin bar 74. By this arrangement the ear portion 104 disclosed in Fig. 10 is eliminated and the nut 124 substituted therefor.

Instead of having a fixed closure for the portion of the opening below the fabricated window frame, a movable closure, either pivotally attached or slidably mounted, or otherwise secured in position, 5 may be used for closing the area below the fixed fabricated window and the bottom of the opening in the wall, so as to utilize this opening as a ventilating area.

In Fig. 14 another modification for forming the 10 rabbet along the bottom of the window has been disclosed. In this modification the lower muntin bar 74 of the fabricated window structure supports a suitable studding 130 extending from the muntin bar to the top line 132 of the masonry 15 when it is placed in position. The studding 130 supports a form member 134 which may be suitably dimensioned and held in position by nails 136, screws or the like. Members 130 and 134 are suspended from the muntin bar 74 and may be 20 held in position by suitable nails or screws 138. The form member 134 through member 130 accurately positions the seat or channel in the masonry along the bottom of the window. This is very 25 desirable, in that the seat along the bottom of the window wants to be properly aligned, so that the glazing of this lower portion may have its place in relationship to both the window members 74 and the masonry.

Instead of forming the sill in situ, that is, 30 pouring the concrete into the forms below the window and positioning the bolts therein or the channels therein, as the case may be, the sill may be molded elsewhere or fabricated and then placed in position while the building is constructed. In 35 this event, the bolts would then be embedded in the sill while it is manufactured or the proper channels or other securing means formed and the bolts or the securing means properly aligned with the fabricated portion of the window frame terminating in spaced relation from the sill, so as to 40 accommodate any suitable type of closure for closing the space between the lower edge of the window frame and the bottom of the window opening.

45 Masonry, as used in the specification and claims, has been used to designate generically the building material used, such as concrete, stone, brick, tile, molding materials, or any other suitable building material.

50 Although the preferred modification of the device has been described, it will be understood that within the purview of this invention various changes may be made in the form, details, proportion and arrangement of parts which generally stated consist in a device capable of carrying out the objects set forth, in the novel parts, combination of parts and mode of operation, as disclosed and defined in the appended claims.

60 Having thus described my invention, I claim:

1. A window assembly for use in an opening in a wall of masonry, said assembly including a metallic frame mounted in spaced relation from the bottom of the window opening so as to leave an 65 open space between the frame and the bottom of the opening, and a window pane disposed in the space found between the window frame and the bottom of the window opening.

2. A window assembly for use in an opening in 70 a wall of masonry, said window including a metallic frame structure mounted in the window opening in spaced relation from the bottom thereof, said frame structure terminating in a muntin bar along the bottom thereof, said muntin bar being disposed in spaced relation from

the bottom of the window opening, and a window pane disposed below the metallic frame structure, said window pane having its upper edge supported on said muntin bar and the bottom edge seated upon the masonry extending across the bottom of the window opening. 5

3. A detention window assembly including a frame structure having a plurality of detention bars held in fixed spaced relation by a plurality of transversely disposed muntin bars, the frame assembly being arranged in spaced relation from the masonry extending across the bottom of the window, window panes supported upon the muntin bars, and a window pane extending across the bottom of the window opening having its upper edge supported by the lowest muntin bar and having the bottom edge seated in the masonry across the bottom of the window. 10

4. A detention window assembly including a rail guard having a plurality of vertically disposed detention bars terminating in spaced relation from the bottom of the window opening and a plurality of transversely disposed duo-functional rail and muntin bars for holding the detention bars in fixed spaced relation, the lowest muntin bar being disposed in spaced relation from the bottom of the window opening, said lowest muntin bar cooperating with the bottom of the window opening to form a space too small for the ingress and egress of a human body, and 20 glazing extending over said space. 25

5. A detention window assembly for a window opening in a wall of masonry, said assembly including a rail guard having a plurality of vertically disposed detention bars terminating in spaced relation from the bottom of the window opening and a plurality of transversely disposed duo-functional rail and muntin bars for holding the detention bars in fixed spaced relation, the lowest muntin bar being disposed in spaced relation from the bottom of the window opening, said lowest muntin bar cooperating with the bottom of the window opening to form a space too small for the ingress and egress of a human body, means embedded in the masonry across the bottom of the window for reenforcing said lowest muntin bar, and glazing extending over said space, said glazing having the lower edge supported upon the masonry. 40 45

6. A detention window assembly for a window opening in a wall of masonry, said assembly including a rail guard having a plurality of horizontally disposed duo-functional muntin and rail bars having the opposite ends embedded in the masonry bounding the window opening and a plurality of vertically disposed detention bars interlocking the muntin bars, the detention bars projecting through the lowest muntin bar but terminating in spaced relation from the masonry extending across the bottom of the window, and means embedded in the masonry extending along the bottom of the window projecting upwardly to engage at least one of the detention bars to reinforce the window assembly. 50 55 60

7. A detention window assembly for a window opening in a wall of masonry, said assembly including a rail guard having a plurality of horizontally disposed duo-functional muntin and rail bars projecting into the masonry along the opposite sides of the window opening and a plurality of vertically disposed detention bars passing through openings in the duo-functional muntin and rail bars, the detention bars terminating in spaced relation from the masonry extending across the bottom of the window opening, and a 70 75

tubular member embedded in the masonry along the bottom of the window projecting upwardly and encircling the lower end of one of the detention bars to reenforce the bottom of the rail guard.

5 8. A detention window assembly for a window opening in a wall of masonry, said assembly including a rail guard having a plurality of horizontally disposed duo-functional rail and muntin bars projecting into the masonry along the sides 10 of the window opening and a plurality of vertically disposed detention bars interlocking the rail bars, the detention bars terminating in spaced relation from the masonry extending across the bottom of the window, the lowest duo-functional 15 detention and muntin bar cooperating with the masonry extending across the bottom of the window to form a space too small for the free ingress and egress of a human body therethrough, and 20 a tubular member embedded in the masonry along the bottom of the window projecting upwardly to encircle one of the detention bars, said tubular member having an outwardly projecting web adapted to extend intermediate adjacent 25 window panes so as to form a support therefor, the tubular member reenforcing the bottom of the rail guard.

9. A detention window assembly for use in a window opening in a wall of masonry, said assembly including a rail guard having a plurality of horizontally disposed duo-functional muntin and detention bars having apertures and projecting into the masonry bounding the window, each of said duo-functional muntin and rail bars including a downwardly projecting flange on one side and a downwardly projecting H-shaped cross sectional structure on the other side and a plurality of vertically disposed detention bars passing through openings in the duo-functional 35 muntin and rail bars and extending intermediate the downwardly projecting flange and the H-shaped structure, the detention bars terminating in spaced relation from the masonry extending across the bottom of the window but below the lowest duo-functional muntin and rail 40 bar, and a tubular reinforcing member embedded in the masonry extending across the bottom of the window, said tubular member projecting upwardly to encircle the lower end of one of the 45 detention bars and having its upper end seated between the detention bar and the flange on the one side and the detention bar and the H-shaped structure on the other side, the flange and the H-shaped structure providing a rainshed for the 50 upper end of the tubular member.

55 10. A metallic window assembly for use in a window opening in a wall of masonry, said assembly including a metallic frame terminating in spaced relation from the bottom of the window opening so as to leave an open space between the frame and the bottom of the opening, rust 60 resisting reenforcing means secured at spaced intervals to the masonry along the bottom of the opening, said means projecting upwardly so as to engage and reenforce the lower portion of the metallic frame.

65 11. A window assembly for use in a window opening in a wall of masonry, said assembly including a metallic frame mounted in spaced relation from the bottom of the window opening so as to leave an open space between the frame and the bottom of the opening, and a tubular reenforcing member secured to the masonry along 70 the bottom of the window projecting upwardly 75

so as to engage and reenforce the lower portion of the metallic window frame.

12. A window assembly for use in a window opening in a wall of masonry, said assembly including a metallic frame having a plurality of vertical muntin bars, said metallic frame, including said muntin bars, terminating in spaced relation from the bottom of the window opening so as to leave an open space between the frame and the bottom of the opening, and a rust 10 resistant reenforcing member secured to the masonry extending along the bottom of the opening and projecting upwardly into engagement with the lower portion of the metallic frame so as to 15 reenforce the same.

13. A window assembly for use in a window opening in a wall of masonry, said assembly including a metallic frame having vertically disposed muntin bars arranged in spaced relation, said metallic frame, including said muntin bars, 20 terminating in spaced relation from the bottom of the window opening, so as to leave an open space between the frame and the bottom of the opening, and reenforcing means aligned with at least one of the muntin bars and secured to the 25 masonry extending along the bottom of the window projecting upwardly into engagement with the window frame so as to reenforce the same.

14. A metallic window assembly for use in a window opening in a wall of masonry, said window assembly including a metallic frame having a plurality of vertically disposed bars arranged in spaced relation, said metallic frame, including the bars, terminating in spaced relation from the bottom of the window opening so as to leave an 30 open space between the metallic frame and the bottom of the opening, an annular portion aligned with one of said bars and projecting downwardly a short distance from the bottom of the metallic frame but in spaced relation from 35 the masonry along the bottom of the window opening, and a tubular reenforcing member secured to the bottom of the masonry projecting upwardly and snugly enclosing said downwardly projecting annular portion so as to reenforce the 40 bottom of the metallic frame.

15. A metallic window assembly for use in a window opening in a wall of masonry, said window assembly including a metallic fabricated main frame having a plurality of transversely 50 disposed muntin bars dividing the window into a plurality of spaces, said main frame terminating in spaced relation from the bottom of the window opening so as to leave an open space between the main frame and the bottom of the window opening, and an auxiliary frame mounted 55 beneath said main frame, said auxiliary frame being movable outwardly without disturbing the main frame.

60 16. A metallic window assembly for use in a window opening in a wall of masonry, said window assembly including a metallic fabricated main frame having a plurality of transversely disposed muntin bars dividing the window into 65 a plurality of spaces, said main frame terminating in spaced relation from the bottom of the window opening so as to leave an open space between the main frame and the bottom of the window opening, and an auxiliary metallic frame 70 for the space below the main frame, said auxiliary frame constituting a unitary cast metal structure having a plurality of upwardly projecting muntin bar sections aligned with muntin bars 75 of the main frame, said auxiliary frame being

removably attached in position for replacement without disturbing the main frame.

17. A metallic window assembly for use in a window opening in a wall of masonry, said window assembly including a metallic fabricated main frame having a plurality of transversely disposed muntin bars dividing the window into a plurality of spaces, said main frame terminating in spaced relation from the bottom of the window opening so as to leave an open space between the main frame and the bottom of the window opening, and auxiliary means for supporting sheet material extending below the main frame, said auxiliary means including muntin bar sections removably attached in position to permit replacement of said auxiliary means without disturbing the main frame.

18. A metallic window assembly for use in a window opening in a wall of masonry, said window assembly including a metallic fabricated main frame having a plurality of transversely disposed muntin bars dividing the window into a plurality of spaces, said main frame terminating in spaced relation from the bottom of the window opening so as to leave an open space between the main frame and the bottom of the window opening, and auxiliary means for supporting sheet material mounted below the main frame, said auxiliary means including a plurality of muntin bar sections, each of which has one end attached to the main frame and the other end attached to the masonry extending along the bottom of the window opening.

19. A metallic window assembly for use in a window opening in a wall of masonry, said window assembly including a metallic fabricated main frame having a plurality of transversely disposed muntin bars dividing the window into a plurality of spaces, said main frame terminating in spaced relation from the bottom of the window opening so as to leave an open space between the main frame and the bottom of the window opening, and auxiliary means for supporting sheet material below the main frame, said auxiliary means including a cast metal frame structure having upwardly projecting muntin bar portions, each of the upwardly projecting muntin bar portions having rivets cast therein, said rivets projecting through the bottom of the main frame for holding the auxiliary means in fixed relation with respect to the main frame.

20. A metallic window assembly for use in a window opening in a wall of masonry, said window assembly including a metallic fabricated main frame having a plurality of transversely disposed muntin bars dividing the window into a plurality of spaces, said main frame terminating in spaced relation from the bottom of the window opening so as to leave an open space between the main frame and the bottom of the window opening, auxiliary means for supporting the glazing extending below the main frame, said auxiliary means including muntin bar sections having the lower ends in contact with the masonry extending along the bottom of the opening and the upper ends in engagement with the lowest muntin bar of the main frame, and means for

securing said muntin bar sections in position, said means including a nut fixedly attached to the muntin bar cooperating with a bolt passing through the lowest muntin bar and threadedly engaging the nut.

21. A metallic window assembly for use in a window opening in a wall of masonry, said window assembly including a metallic fabricated main frame having a plurality of transversely disposed muntin bars dividing the window into a plurality of spaces, said main frame terminating in spaced relation from the bottom of the window opening so as to leave an open space between the main frame and the bottom of the window opening, the bar extending across the bottom of the frame having a downwardly projecting flange, and closure means having a greater resistance to corrosion than the main frame of the window for closing the space intermediate the main frame and the bottom of the window opening, said closure means including sealing material engaging one side of said downwardly projecting flange.

22. A metallic window assembly for use in a window opening in a wall of masonry, said window assembly including a metallic fabricated main frame having a plurality of transversely disposed muntin bars dividing the window into a plurality of spaces, said main frame terminating in spaced relation from the bottom of the window opening so as to leave an open space between the main frame and the bottom of the window opening, the bar along the bottom of the window having a downwardly projecting flange, the masonry across the bottom of the window having a vertical shoulder, and closure means for the opening below the main frame, said closure means having sealing material contacting the downwardly projecting flange and sealing material on the opposite side of the closure means for contacting the shoulder to provide water tightness.

23. A rail guard window assembly including guard bars, horizontal muntin bars provided with glazing seats for supporting glazing above and below the muntin bar, said muntin bar including a guard bar supporting portion projecting outwardly from the glazing sloping downwardly from the edge of the glazing so as to provide water drainage and terminating in a downwardly directed flange portion strengthening the muntin bar.

24. A metallic window assembly for use in an opening in a wall of masonry, said assembly including a metallic frame having at least one horizontally disposed muntin bar extending across the bottom of the frame arranged in spaced relation from the masonry extending across the bottom of the window, glazing mounted in the window frame and a closure for the space between the bottom of the frame and the masonry extending across the bottom of the window opening, said closure having its lowest edge supported upon the masonry and the upper portion in contact with said frame.

WILLIAM D. BAYLEY.
